UNITED STATES PATENT OFFICE

JAMES R. BALSLEY, OF BEVERLY HILLS, CALIFORNIA, ASSIGNOR TO FOX FILM CORPORATION, OF HOLLYWOOD, CALIFORNIA, A CORPORATION OF NEW YORK

SOUND RECORDING SYSTEM

Application filed November 18, 1929. Serial No. 407,924.

This invention has to do with the photographic recording of sound; and has for a general object the provision of a sound recording system characterized by high light efficiency and faithfulness of recordation.

According to the present invention the film is light-affected for the purpose of recording, by a corona discharge from an electrode charged by an audio-frequency modulated oscillating current. The corona discharging electrode may be formed, for instance, with a thin discharge edge mounted parallel to and in alinement with a suitable light slit before which the film is moved. The electrode may be included in a circuit inductively coupled to an oscillation circuit carrying the modulated oscillating current, the ratio of coupling being such that a sufficiently high potential to permit corona discharge is provided for the electrode.

Among the advantages of this system may be mentioned, first, that the glow of a corona discharge is very actinic in character, and second, that the discharge electrode may be located very much closer to the film than may the usual present used glow lamp. Both of the above factors contribute toward increased density in the sound record for a given amplified microphone current and a given light slit. It is well known that the accuracy of reproduction is increased as the width of the light slit is decreased, but that the narrowness of the slit is limited by the lowest light intensity which will give a suitable density on the film. According to the present invention it is possible to decrease the width of the light slit for accuracy of reproduction, while the highly actinic character of the corona glow insures proper density on the film.

The invention will be best understood from the following detailed description of a present preferred embodiment thereof, reference for this being had to the accompanying drawing, in which:

Fig. 1 is a diagram of typical apparatus and electrical circuits embodying my invention;

Fig. 2 is a view taken on line 2—2 of Fig. 1; and

Fig. 3 is a view taken on line 3—3 of Fig. 1.

Referring now to the drawing, Fig. 1 shows the electrical circuit preferably embodied in my recording system. The microphone M produces electrical waves corresponding to the sound impressed thereon. These waves are transmitted to the amplifier 10, conventionally illustrated as being of the vacuum-tube type but which may be of any type capable of amplifying waves without substantial distortion. The output of amplifier 10 is connected to the modulator-oscillator circuit, generally indicated by the numeral 12, which may be of the well known "Heising circuit" type.

This circuit includes an oscillator tube 20 and a modulator tube 21, the respective plates P_o and P_m of which are both supplied with direct current from a battery B through a low-frequency choke coil D, which coil tends to maintain a direct current of constant magnitude through the two plate circuits in parallel. When the microphone is not in action the potential difference across coil D and battery B is constant, and the tube 20 and its oscillation circuit L_1C generate a high-frequency oscillating current of constant amplitude. When, however, the microphone M is being acted upon by a sound wave, an audio-frequency electromotive force is impressed upon the grid circuit of the modulator, which causes an audio-frequency current to flow in the plate circuit thereof. Consequently the direct current supply to the plate circuit of the oscillator tube, and hence its electro-motive force and the amplitude of the high-frequency current flowing therein, is varied or modulated in accordance with the impressed audio-frequency wave.

A coil L_2 is inductively coupled to the coil L_1 of circuit 12, coil L_2 having a large number of turns relative to coil L_1 so that the electromotive force induced therein will be high. Coils L_1 and L_2 thus constitute a step-up transformer with coil L_2 carrying a high-tension current. Coil L_2 is connected to a wire 25 which leads to a corona-discharge electrode 26. Electrode 26 has a thin razor-edge 27 which, under the potentials applied thereto, glows with a corona discharge. Disposed before the electrode razor-edge 27 and

parallel thereto is a narrow light-slit 28 which may be formed, for instance, by cutting a thin line through a silver coating 29 carried on a transparent base 30. The silver 29, which is connected to ground, is sufficiently spaced from the discharge electrode that under the potentials applied thereto no sparks will jump across the gap, so that a corona discharge only appears at the electrode. A film F on which the sound record is to be made is longitudinally moved transversely to slit 28 and electrode-edge 27 by means of a sprocket 31 meshing with film perforations 32.

15 In operation, the audio-frequency-modulated high-frequency current of the oscillation circuit induces a current in coil L_2 , and the turn ratio of L_1 to L_2 being such that a sufficiently high potential appears at the 20 razor-edge 27 of electrode 26 to cause a corona discharge therefrom, the electrode glows with a light intensity that varies with the audio-frequency modulations. The light from this varying corona discharge is transmitted through slit 28 and affects the longitudinally moving film F, producing thereon a varying density audio-frequency record 35.

25 The highest potential for electrode 26, and the least loss in the system, is attained when 30 the system is so arranged and balanced that the effective length of coil L_2 , and wire 25 out to the end of the discharge electrode 26 is an integral multiple of the fundamental oscillating frequency wave length of the oscillation circuit. In such a case the reflected wave 35 from the electrode end of wire 25 is in phase with and aids the forwardly traveling wave, and causes the potential at the electrode to reach its highest possible values for a given 40 set of conditions. This balance could be realized by determining the length of wire 25 in accordance with the fundamental frequency of the oscillation circuit; but it is most easily obtained by varying the fundamental 45 frequency of the oscillation circuit into accordance with the effective length of coil L_2 and wire 25 by means of the variable condenser C. Therefore, in practical operation, I prefer to vary condenser C until 50 a voltage peak is produced at the point of discharge.

55 The discharge edge 27 of electrode 26 may be arranged quite close to the film, and, since a corona discharge is very actinic in character, a high light intensity and hence a high density on the film is obtainable even with the use of a slit of narrower width than has heretofore been possible with any prior system of which I am aware. And since, as 60 is well understood in the art, the faithfulness of recording is inversely proportional to the width of the slit, within the limits of proper density on the film, the system is therefore capable of recording sound with 65 greatly improved accuracy.

It will be understood that the specific system described herein is merely illustrative of and not restrictive on the invention, and the following claims therefore embrace all such modifications and equivalent arrangements as may fairly be construed to lie within the scope of my invention.

I claim:

1. In a sound recording system, the combination of an electrical vacuum tube oscillator having an oscillation circuit including an inductance and a capacitance, means for modulating the oscillating current in said circuit in accordance with an audio-frequency input current, a high-tension secondary circuit coupled to said oscillating circuit, a razor edge electrode energized by high tension current induced in said secondary circuit, an electrically conductive means forming a light slit before and parallel to said razor edge electrode, said light slit means being included in said high tension secondary circuit, and the spacing between the razor edge of the electrode and the light slit means being such that a corona discharge takes place therebetween and illuminates the light slit, and means for moving an actinic film before and transversely to said light slit.

2. In a sound recording system, the combination of an electrical vacuum tube oscillator having an oscillation circuit including an inductance coil and a condenser, the fundamental oscillation frequency of said circuit being variable by relative adjustment of its inductance and capacitance, means for modulating the oscillating current in said circuit in accordance with an audio frequency input current, a secondary coil connected to said oscillation circuit and inductively coupled to the inductance coil of said circuit, a razor edge electrode connected to the other side of said secondary coil, the oscillation frequency of the oscillator being adjusted with respect to the effective length of the electrode circuit so as to give a potential peak at said razor edge a grounded electrically conductive means forming a light slit before and parallel to said razor edge electrode, the spacing between said razor edge and said light slit means being such that a corona discharge takes place therebetween and illuminates the light slit, and means for moving an actinic film before and transversely to said light slit.

5 In witness that I claim the foregoing I have hereunto subscribed my name this 17 day of September 1929.

JAMES R. BALSLEY.
